PROJECTILE FOR SMOOTH BORE WEAPONS

Edgar William Brandt, Paris, France, assignor
to Sageb, Société Anonyme de Gestion et d'Ex-
ploitation de Brevets, Fribourg, Switzerland,
a corporation of Switzerland

Application March 11, 1937, Serial No. 130,402
In France March 13, 1936

1 Claim. (Cl. 102—29)

This invention relates to a projectile intended to be fired from smooth bore weapons, such as mortars, trench mortars and the like. It is more particularly suitable for weapons of this kind 5 firing with initial velocities of 100 to 400 metres per second.

The projectile of the present invention is of the type comprising an ogival frontal portion, connected by a cylindrical portion with a tapering 10 rearward portion to which is attached a cylindrical tail, the extremity of which carries stabilizing vanes.

The projectile of the present invention is primarily characterized in that the several component portions thereof have the following approximate longitudinal dimensions, expressed in 15 calibres:

Ogival portion	2
Cylindrical portion	0.65
Tapering rearward portion	2.2
Cylindrical tail	1.7 and 0.65
Vanes	0.65

making a total length of about 7.2 calibres. The 25 length of one or more of the parts of the projectile may vary by $\pm 10\%$.

According to another characteristic of the invention, the whole is so arranged that the centre of gravity of the loaded projectile is located at 30 a point about 0.40 calibre behind the rear extremity of the cylindrical portion, whilst the centre of resistance is at a point about 1 calibre behind the rear extremity of said cylindrical portion.

The foregoing arrangement ensures the maximum range of the projectile with a given propellant charge, and at the same time, a high degree of accuracy.

Further features and advantages of the invention will become apparent from the following further description thereof.

In order more clearly to understand the invention, reference is made to the accompanying drawing, which illustrates diagrammatically and 45 by way of example, one embodiment thereof and in which:

Fig. 1 is an elevation; and

Fig. 2 is an end view.

The embodiment illustrated is intended to represent a 120 mm. projectile, the projectile comprising a frontal portion 1, in the form of a slender ogive with an angle of ogive between 35 and 45°, and carrying the fuse 2.

The total length of the ogival portion and fuse 55 is about 2 calibres.

The ogive 1 connects, preferably tangentially, with a cylindrical portion 3, provided with sealing grooves 4, of known type, forming a pneumatic joint between the projectile and the walls of the bore of the gun. The length of this band is 5 about 0.65 calibre.

Beyond the band 3, the body of the projectile comprises a portion 5 which tapers towards the rear (in the form of a cone, ogive or otherwise) and has a length of about 2.2 calibres. 10

The walls of the projectile become stouter as they advance from the band 3, so that, near the forward extremity, at 6, they are about twice as thick as the walls of the band, at 7. Over the whole length of the rearward portion 5, the 15 thickness of the walls remains approximately the same as in line with the band, and does not increase until the base, at 8.

The body of the projectile terminates in a 20 cylindrical heel 9, to which is attached an also cylindrical tail 10 serving to support radial vanes 11. The length of the cylindrical portion comprised between the rear edge on the part 5 and the root of the vanes is about 1.7 calibres. The diameter of this portion of the projectile is preferably a little smaller than that of the rear edge 25 12a. The length selected for the vanes 11 is about 0.65 calibre. As shown in the drawing, the leading edges 12 of the vanes are preferably given a backward sweep in relation to the direction of flight of the projectile. Projections 13 on the rear ends of the vanes serve to guide the projectile in the gun. 30

The tail 10 is of tubular form, and houses 35 the propellant charge (cartridge), the gases of which escape through the openings 14. Supplementary charges 15, for example, of horse-shoe pattern, may be placed round the tail, between the vanes and the body of the projectile in order to increase the range. Charges of this kind are 40 described in the U. S. Patent No. 2,052,546 dated September 1, 1936. A small collar 15a, or equivalent checking device, may be provided on the tail 10, to prevent the charges 15 from slipping beyond the region of the openings 14. The proportions specified for the several portions of the projectile are given merely by way of approximation as previously stated, one or more of them 45 may vary by $\pm 10\%$.

The projectile is arranged in such a manner that 50 the centre of gravity G of the loaded projectile is preferably located at a point about 0.40 calibre behind the rear end of the cylindrical zone; the centre of resistance R (point of application of the resultant of the aerodynamic pressures on the 55

projectile) being located at a distance comprised between 0.90 and 1.5 calibres behind the rear end of the said cylindrical zone.

It is obvious that the invention is capable of 5 various modifications and alterations without departing from the spirit and scope thereof as defined in the appended claim.

I claim:

A projectile for smooth-bore weapons comprising 10 a body including consecutively from the front to the rear thereof, an ogival front part, a full calibre cylindrical guiding part engaging the bore of the weapon and into which said ogival front part merges, and a rearward tapering part; a tail 15 fixed to the rear end of said body, vanes mounted at the rear end of said tail and having the same diameter as that of said cylindrical guiding part, and a fuse at the front end of said body adapted

to cause bursting of the projectile; the length of said ogival front part with said fuse being between 1.8 and 2.0 calibres, the length of said cylindrical guiding part being between 0.65 and 0.72 calibres, the length of said rearward tapering 5 part being between 2.20 and 2.42 calibres, the length of said tail up to the front side of said vanes being between 1.60 and 1.75 calibres and the length of said vanes being between 0.65 and 0.75 calibres; the center of gravity of the projectile being located at a distance of between 0.35 and 0.45 calibres in rear of the rear end of said cylindrical guiding part and the center of resistance being located at a distance of between 1.30 and 1.50 calibres in rear of the rear end of 15 said cylindrical guide part.

EDGAR WILLIAM BRANDT.
